UNITED STATES PATENT OFFICE.

EDWARD POOLE, OF HALIFAX, ENGLAND, ASSIGNOR TO JOSEPH WILD
& CO., OF NEW YORK, N. Y.

DESIGN FOR A CARPET-PATTERN.

Specification forming part of Design No. 5,802, dated April 16, 1872.

Specification describing a new and original Design for a Carpet, invented by EDWARD POOLE, of Halifax, in the county of York, England.

The accompanying photograph fully represents my new design.

This invention relates to a new carpet design, containing, as novel, two ornamental figures within a ground of scrolls of suitable kind.

The larger of the two figures is of octagonal form, with alternate straight and concave sides, and contains within it a regular octagon, in

which a bunch of flowers forms the filling. The smaller of the two figures is also of octagonal form, and has a bouquet of flowers in the middle, and rectangular shields on every other side, as shown.

I claim as my invention—

The design for a carpet containing the two octagonal figures, as shown.

EDWARD POOLE.
